NONFOULING DRILL

Wade Vanderpool, Stevenson, Wash., assignor of
one-half to Dee Wakefield, Stevenson, Wash.

Application January 28, 1937, Serial No. 122,863

7 Claims. (Cl. 255—69)

This invention relates to rock drills and is particularly adapted for use on jack hammers wherein a fluid operated motor on the hammer imparts power pulsations to the drill and at the same time the drill rotates in a counter clockwise direction relative to the top of the drill under the influence of the cutting action. The present invention is a continuation in part of my pending U. S. Patent application Serial 10 82,092 filed May 27, 1936.

The primary object of the invention is to provide, either as an integral or a separate part, the lower end of the drill rod with fins or blades arranged in a spiral, the said fins or blades having extension wings projecting below the connection of the end of the drill rod and bit, and which wings snugly fit over the part or parts on the drill bit where fouling is likely to occur.

Another feature of the present invention is to 20 construct the blades or fins in a manner to grind or crush any obstacles in the drill holes immediately above the drill bit cutting edge so that the crushed or ground obstacles may be blown out of the hole with air, and which blades or 25 fins force the cuttings downward at the same time the drill and bit are forced upward in event the drill is fouled in the drill hole all of which is performed without interfering with the efficient operation of the drill.

Further objects of the invention are to provide a device of the character referred to that is strong, compact, durable, thoroughly reliable for its intended purpose, very simple to manipulate and comparatively inexpensive to manufacture.

With the foregoing and other objects in view the invention consists in the novel construction, combination, and arrangement of parts as will be hereinafter more specifically described and illustrated in the accompanying drawings wherein is disclosed an embodiment of the invention, but it is to be understood that changes, variations, and modifications may be resorted to without departing from the spirit of the claims hereunto appended.

In the drawings wherein like reference characters indicate like parts through the several views:—

50 Figure 1 is an exploded perspective view of the lower end of a rock drill of customary construction to which the present invention may be attached when it is made in a separate part.

55 Figure 2 is a side elevation partly broken away of one form of the present invention embodied

in a separate part and assembled with the customary drill rod and bit.

Figure 3 is a bottom plan view of either form of the drill constructed in accordance with the present invention.

Figure 4 is a side elevation partly broken away of a modified form of a drill embodying as an integral part of the lower end of the drill rod, the construction of the present invention.

Figures 5 and 6 are sections taken substantially on the planes of lines 5—5 and 6—6 of Figure 4 respectively and looking in the direction of the arrows.

In the drawings A indicates the lower end of a conventional rock drill formed with a reduced threaded pin 8 on its inner end. This drill rod has an axial air passage 1 therein through which air is forced from the surface of the ground downwardly into the hole for blowing out the cuttings. A regulation rock drill bit indicated 20 B, is detachable from the drill rod A when the cutting edge wears so that another bit may be substituted. The outer end of the drill rod A is coupled to the jack hammer (not shown) from which the drill rod receives power pulsations to 25 drill the hole in the rock. As is well known in rock drilling practice that the drill consisting of the coupled drill rod A and the bit B turns slowly in a counter clockwise direction viewing the top of the drill, which rotation is independent of the power impact pulsations. In this specification it is to be understood that the drill rod rotates in a counter clockwise direction looking at the top of the drill rod. The same conventional drill bit is used regardless of whether 30 the invention is embodied as an integral part of the drill rod as shown in Figure 4 or as a separate part as shown in Figure 1.

The regulation drill bit B has a central cylindrical hub 9. For illustration the drill bit selected is of a type having a single angular cutting edge or point 10 as distinguished from those types of multiple radial points or cutting edges known as "Star" or "Rose" bits, and there are oppositely and radially disposed reinforcing ribs 45 11, 12 of right triangular configuration formed integral with the hub 9. These ribs are not as thick as the diameter of the hub 9 and they terminate at their bases in line with the inner end of the hub 9 to form the single edge 10 across corresponding bases of the triangular ribs and the end of the hub. Corresponding altitudinal sides of the triangular ribs 11 and 12 merge with the periphery of the hub 9 in an axial direction, but they do not extend to the top of the hub 9, 50 55

and this formation leaves a circular shoulder $9a$ surrounding the upper end of the hub 9 above the juncture of like sides of the triangular ribs corresponding to the hypotenuse. It has been 5 my experience that the cuttings, mud and other obstacles jam or wedge at this shoulder $9a$ and foul the drill. The wings or extensions of my invention prevent this fouling by grinding, cutting or pushing the material downwardly away 10 from this shoulder where they may be blown out of the hole.

There is a threaded socket 13 in the upper or outer end of the hub 9 and there is an air duct 14 extending from the inner wall of the socket that 15 has an outlet on a flat diagonal segment 15 on the periphery of the hub 9 at the inner end of the hub. As is the practice in rock drilling, air is introduced through passage 7 to this duct 14 to blow cuttings, dirt and mud free of the cutting 20 edge 10 and out of the hole.

The principle of the invention is the same regardless of whether it is applied as an integral part at the inner end of the drill rod, as illustrated in Figure 4, or as a detachable part as 25 shown in Figure 2. In both cases, the regulation bit B as heretofore described is used. The only difference in construction is that where the conventional drill rod A' has the shank 16 as a continuation at the inner end of the drill rod as 30 shown in Figure 4 it will have a reduced threaded pin $8a$ detachably seated directly in the socket 13 of the bit B; whereas in the modified form shown in Figure 2 where the part is separate, the shank 16 has a threaded socket 17 at the upper or outer 35 end which receives the threaded pin 8 on the conventional drill rod A. Where the invention is embodied as a separate part it has a reduced threaded end $8b$ on the lower or inner end of shank 16 which screws into socket 13 in the conventional bit B.

In either form of the invention the shank 16 is an elongated cylindrical body formed with an axial air passage 18 . This passage 18 registers with passage 7 at one end and the duct 14 at the 45 other end where the invention is embodied as a separate part as shown in Figure 2; while it is a continuation of the air passage of the drill rod on which it is formed where the invention is incorporated as an integral part as shown in Figure 4.

50 Formed on the periphery of the shank 16 are a pair of oppositely disposed spirally arranged outset blades or fins $19-19$ which retreat one half turn or 180° , from the outer or upper end to the inner or lower end when the shank rotates in a 55 counter clockwise direction. The fins or blades are continuous throughout the length of the shank. The inner or lower ends of the ribs continue below the end of shank 16 to form extension wings $19a-19a$ which overhang and overlap 60 the shoulder $9a$ and the upper or outer portion of the sides of the triangular ribs corresponding to the hypotenuse.

The leading faces $19b-19b$ of the fins $19-19$ and wings $19a-19a$ are flat, while the trailing faces $19c-19c$ are curved on substantially the same radius of the shank 16 . At the outer or upper end the fins merge with the periphery of the shank from which point they progressively increase in height in a radial direction relative to 70 the shank, to the ends of the extensions or wings $19a-19a$. The confronting edges of the wings $19a-19a$ form an obtuse angle having corresponding edges 20 snugly yet movably fitting flush against shoulder $9a$ and the corresponding edges 75 21 fitting flush against the sides of the ribs cor-

responding to the hypotenuse so as to permit replacement of the bit B.

The flat leading faces $19b$ on the wings $19a$ are flush with the leading sides of the triangular ribs when the drill bit B is screwed home. Where the flat face $19b$ of the fin merges with the curved face $19c$ there is a sharp edge which acts as a spiral inclined cam that raises the drill free when it becomes fouled and this edge is also sharp enough to grind and reduce in size, any large 10 cuttings that are too large to be blown out of the drill hole. It is also pointed out that the distance between the sharp edges on the fins is less than the width of the cutting point 10 to provide clearance. Between the curved trailing face $19c$ 15 of the one fin and the flat leading face $19b$ on the other fin there are spiral sumps or canal one opposite the other, where the cuttings, by reason of the counter pitch or retreat curvature of the fins are normally forced inwardly or downwardly by 20 the counter clockwise rotation of the drill.

Having thus described my invention, what is claimed is:—

1. In combination, a drill rod, a drill bit, co-acting means on the rod and bit for detachably 25 coupling them together, said drill rod carrying spiral fins formed with wings which overlap a portion of the drill bit when the rod and bit are coupled together to prevent fouling of the 30 bit.

2. In combination, a drill rod, a drill bit, a member detachably connected to the rod and bit and formed with spiral fins and said fins having depending wings at one end overlapping a portion of the drill bit to prevent fouling of the 35 bit.

3. In combination, a drill rod, a drill bit detachably connected to one end of the drill rod, said drill rod formed with integral spiral fins 40 on a portion at the said one end, and said fins terminating in depending wings overlapping a confronting portion of the drill bit to prevent the fouling of the bit.

4. In a drill of the jack hammer type, the combination with a drill rod and a detachable bit 45 of spiral fins carried by a portion of the rod having wing extensions on the fins overlapping a confronting portion of the bit to prevent fouling of the bit usually caused by the shoulder structure of the conventional jack hammer drill bit. 50

5. In a drill of the jack hammer type, the combination with a drill rod and a detachable bit of spiral fins carried by a portion of the rod having wing extensions on the fins overlapping a confronting portion of the bit to prevent fouling 55 of the bit usually caused by the shoulder structure of the conventional jack hammer drill bit, said fins being spiraled in a direction counter to the direction of rotation of the bit to direct downwardly the cuttings that otherwise tend to 60 foul the bit.

6. In a drill of the jack hammer type, the combination with a drill rod and a bit, of a member adapted to be interposed between one end of the rod and the bit and serving to connect the bit 65 to the rod, said member including a substantially cylindrical body having spiral fins thereon, said fins having end portions terminating beyond the lower end of said body and disposed at opposite sides of and in edge contact with said bit to prevent fouling of the bit usually caused by the shoulder structure of the conventional jack hammer drill bit. 70

7. In a drill of the jack hammer type, the combination with a drill rod and a bit, of a member 75

adapted to be interposed between one end of the rod and the bit and serving to connect the bit to the rod, said member including a substantially cylindrical body having spiral fins thereon, said fins having end portions terminating beyond the lower end of said body and disposed at opposite sides of and in edge contact with said bit to prevent fouling of the bit usually caused by

the shoulder structure of the conventional jack hammer drill bit, said fins being spiralled in a direction counter to the direction of rotation of the bit and serving to direct downwardly wet or heavy cuttings that otherwise tend to foul the bit. 5

WADE VANDERPOOL.
